UNITED STATES PATENT OFFICE.

FREDRICK HOWARD AULD, OF COLUMBUS, OHIO.

DEVICE FOR SECURING NAME-PLATES AND THE LIKE.

1,263,994.

Specification of Letters Patent. Patented Apr. 23, 1918.

Application filed March 18, 1916. Serial No. 83,997.

To all whom it may concern:

Be it known that I, FREDRICK HOWARD AULD, a citizen of the United States, residing at Columbus, in the county of Franklin and State of Ohio, have invented a certain new and useful Improvement in Devices for Securing Name-Plates and the like, of which the following is a specification.

Some forms of name plate having a securing device attached thereto require the application of pressure to the securing device from the interior side of the structure to which the name plate is to be applied to expand it into securing position. Often times, however, it is inconvenient or entirely impracticable to introduce such pressure, hence the object of this invention is an improved construction whereby a name plate or other article can be secured by merely pressing the plate and its securing member into proper position from the exterior of the structure to which the name plate is to be applied. A further object of the invention is an improved form of securing member whereby the connection of the name plate with the article to receive the same is made firmer.

The invention is embodied in the construction herein shown and described and then finally claimed.

In the accompanying drawing—

Figure 1 is a central sectional view through a wall having a hole and a name plate and its securing member, the name plate and its securing member being shown as resting over the hole in position to be pressed into its final place.

Fig. 2 is a similar view showing the name plate pressed into secured position.

Fig. 3 is a plan view of the device looking at the lower side of Fig. 2.

Fig. 4 is a section like Fig. 2 of a modification.

In the views 5 designates the wall which may be that of an automobile radiator, piece of furniture or any article to which it is desired to secure a name plate. The wall is made with a suitable hole as seen at 6.

7 designates the name plate which is shown to be of a diameter larger than the hole so as to cover the same.

The securing member consists of a ring or plate of sheet metal annularly bent as shown and secured at its inner edge to a central boss on the rear or lower side of the name plate. In the instance shown an

annular lip 8 on the boss is spun or bent over a lip 9 forming the inner margin of the ring. The securing member is formed by annularly bending it so as to form two zones 10 and 11 standing at an angle to each other with the concave side of the ring facing the name plate. The diameter of the securing ring is made less than that of the name plate but normally of slightly larger diameter than the hole it is to occupy. The inner zone 10 is the narrower one and more nearly approaches or coincides with the direction of the axis of the securing member than the outer zone 11. The inner zone 10 is therefore quite stiff and offers great resistance to stress applied to the outer zone. The outer zone by reason of its width and angular relation to the other zone and name plate is sufficiently yielding under pressure applied to the name plate to enter the hole 6 provided for it as illustrated in Figs. 1, 2 and 3. When pressed into position as shown in Fig. 2 the outer edge of the securing member grips the walls forming the hole 80 with great tenacity, even if the wall be of metal and the hole of the ordinary boring or punching. My experience has been that when properly made the name plate can only be removed by a virtual destruction of the securing member.

In Fig. 4 a countersink in the wall is provided to receive the name plate. In such a construction the name plate will be still more difficult to remove because a prying instrument can not be conveniently pressed under its rim.

The forms of the parts can be changed without departing from the gist of the invention as claimed.

What I claim is:

1. Means for securing one object to another object having a hole, said means consisting of a plate attached to the article to be secured, said plate being bent around its rim to form a resilient edge to engage the surface forming the hole, said plate being normally of slightly larger diameter than the diameter of the hole.

2. Means for securing one object to the surface forming a hole in another object, said means consisting of a plate attached to the article to be secured, said plate being bent around its rim to form zones standing at angles to each other to concave the plate at the side facing the object to be secured.

3. Means for securing one object to the

surface forming a hole in another object, said means consisting of a plate attached to the article to be secured, said plate being bent around its rim to form zones standing at angles to each other to concave the plate at the side facing the object to be secured, the outer of said zones being the wider.

5. Means for securing one object to the surface forming a hole in another object,

said means consisting of a plate attached to the article to be secured, said plate being bent around its rim to form two zones standing at angles to each other, the inner zone being narrower than the outer zone and standing at a smaller angle to the axis of 15 the plate than the outer zone.

FREDRICK HOWARD AULD.
